GAS BURNER

Carroll Cone, Lucas County, Ohio, assignor to
Surface Combustion Corporation, Toledo, Ohio,
a corporation of New York

Application May 12, 1933, Serial No. 670,764

7 Claims. (Cl. 158—104)

The present invention has among its objects to provide a gas burner of such form and construction that gas may be discharged therefrom in spaced parallel streams; that upon being positioned in an air supply conduit the conduit will be divided by the burner into a plurality of parallel passages for the flow of air from the conduit; that the burner may be readily removed from said conduit; that overheating of the gas supplied to the burner may be prevented, and withal to provide a burner which shall be relatively simple in construction and otherwise well adapted for its intended purpose.

The various features of novelty and invention will be more fully described in connection with the accompanying drawings forming part of this specification wherein the preferred form of burner construction is shown and wherein—

Fig. 1 is a sectional view on line 1—1 of Fig. 6 and shows the gas burner as positioned in an air conduit which supplies the air for combustion, the view also showing a portion of the furnace to be fired;

Fig. 2 is a vertical section on line 2—2 of Fig. 6; Fig. 3 is a horizontal section on line 3—3 of Fig. 2;

Fig. 4 is a perspective view of one of the tiles used in the construction of the burner;

Fig. 5 is a section on line 5—5 of Fig. 6, certain refractory parts being omitted, and

Fig. 6 is a transverse section on line 6—6 of Fig. 1 and shows the burner in elevation.

Referring to Figs. 1 and 6, numeral 10 indicates a vertical end wall, 11 is a side wall and 12 the roof of a furnace to be fired. Indicated at A is a rectangular air-supply conduit of substantially the same width as the furnace to be fired, this conduit being shown as formed by an extension of the furnace roof 12, and side walls 13 and 14 and a floor or bottom wall 15. Generally speaking, the arrangement thus far described is similar to that shown in Fig. 1 of Patent No. 1,900,432.

The burner as a whole is generally indicated at B and is supported on a carriage C supported on transversely extending rails 16, the carriage being below the bottom wall or floor 15 of the conduit A as is clearly shown in Fig. 1. The purpose of the carriage is to permit the burner to be moved laterally out of the conduit for inspection and repairs. A portion of the conduit side wall 13 is supported on the carriage as is clearly shown in Fig. 6 and hence it is a simple matter to withdraw the burner from the conduit as will be readily appreciated. Sand seals 17 form a

suitable closure between the top of the carriage C and the under side of the said floor 15.

As is clearly shown in Fig. 6, the burner comprises a plurality of upright bodies 19 arranged in laterally spaced relation to form individual passages 20 through which the air from the conduit A may flow toward the furnace for supporting combustion of the gas discharged from the burner. The said bodies are of a substantial length longitudinally of the conduit A (Fig. 1) and are of substantially the same height as the conduit, and as will more fully appear hereinafter, are each provided with a row of gas nozzles.

The said bodies 19 are individually and removably supported on an elongate base 21 secured to the top of the carriage C. To this end there are secured to the base 21 individual stools 22 having upright flanges 23 between which is confined a refractory bed 24, the stools being chambered for purposes presently appearing.

Each body 19 is preferably made up of a series of tiles 26 of the shape shown in Fig. 4, and the bottom member of each body may be a simple spacer block 25. Each tile has a nozzle 27 and an oblong aperture or slot 28. When the tiles are assembled in vertical series to make up the body 19 as shown in Fig. 2, the slots constitute what may be termed a tunnel.

Gas is supplied to the nozzles 27 by individual nipples 29 which project into the receiving end of the nozzles as is clearly shown in Figs. 2 and 3. The nipples project from a gas pipe 30 which projects upwardly from an individual stool 22, the lower end of the pipe being in direct communication with a gas chamber 31 formed in the stool, said chamber being in direct communication with a main gas chamber 32 formed in the base 21 as is clearly shown in Fig. 5. Gas is delivered to the main gas chamber 32 by a main supply pipe 33.

If the gas flowing through the pipes 30 becomes overheated, it will break down with the liberation of carbon with consequent clogging of the pipes and the nipples 29. To prevent such overheating, the pipes 30 are water cooled. To this end each pipe is surrounded by a hollow post or water jacket 34 to which water is delivered by a pipe 35 which has its discharge terminal near the top of the jacket as is shown in Fig. 2 and which leads from a water chamber 36 in the stool 22, this chamber being in direct communication with a main water chamber 37 in the base 21, water being supplied to this chamber 27 by a pipe 38. The water leaves the jacket by a pipe 55

39 having its inlet at the lower end of the jacket 34, this pipe discharging into a chamber 40 in the stool 22, this chamber being in direct communication with a main receiving chamber 41 in 5 the base 21, the water leaving the chamber 41 by a waste pipe 42. The jacket is of uniform cross section throughout its length, and at its bottom end is closed by being welded to the pipes 30, 35 and 39 at a point above the stool 22. It will be 10 noted that the nipples 29 extend through and project a substantial distance beyond the adjacent side wall of the jacket 34.

In transverse cross section, the jacket is as wide as the slot 28 in the tile 26 but in transverse 15 length it is the shorter by the distance that a nipple 29 projects beyond the wall of the jacket as is clearly shown in Fig. 3. By reason of this construction it is a simple matter to position the tiles 26 on the posts as shown in Fig. 2. Thus 20 referring to Fig. 3, it will be understood that the space 42 is sufficient to permit the tile to be moved toward the right a sufficient distance to disengage the nipple 29 from the receiving end of the nozzle 27. After a tile has been placed 25 on its post 34, the space or gap 42 will be filled with cement, thus keying the tiles on the post or jacket 34.

Since each of the bodies 19 is supported on a stool 22 and since these stools are detachably secured to the base 21 and since the burner as a 30 whole may be readily withdrawn from the conduit A, it will be readily appreciated that it is a simple matter to replace any particular body with a new unit in case necessity demands.

35 It is desired that air from the conduit A shall flow between the bodies 19 in stream-line flow and to this end the individual tiles 26 making up the body are of stream-line form as is clearly shown in Fig. 4. It is also desired that the gas 40 shall be discharged from the nozzles 27 in stream-line flow and to this end the passages which constitute the nozzles are of gradually diverging or stream-line form as is clearly shown in Figs. 2 and 3. From the foregoing description 45 it will be readily appreciated that there will be alternating sheets of air and gas flowing into the furnace. Ordinarily the air and gas will flow from the passages 20 and nozzles 27 at equal and relatively low velocities in order that mixing 50 of the air and gas may proceed relatively slowly with the consequent construction of a relatively long flame.

What I claim is:

55 1. In a gas burner, an elongate base having a gas chamber, a plurality of stools each having a gas chamber in direct communication with the gas chamber in said base, a gas pipe supported by and extending from each stool, a hollow 60 post whereinto each gas pipe projects, a plurality of nipples projecting from each gas pipe and projecting through and beyond the adjacent wall of each post, and means associated with

said stools and base for supplying cooling fluid to said posts.

2. An article of manufacture for a gas burner comprising an elongate body which at one end and for a substantial portion of its length is circular in cross section and which intermediate its ends on a plane at right angles to the axis of the circular portion is rectangular in cross section and which remote from the circular portion of the body is provided with a transversely extending aperture, said circular portion being axially apertured, the two apertures being in communication.

3. In a gas burner, a supporting base, a plurality of elongate bodies supported on said base in upright spaced relation to form passages through which air may flow, each of said bodies being longitudinally apertured, a hollow post in each of said apertures, a series of nozzles projecting in spaced relation from one longitudinal edge of each of said bodies, and means housed by the posts for supplying fuel gas to said nozzles.

4. In a gas burner, the combination of a plurality of elongate bodies each having a transverse aperture therethrough adjacent one end and a longitudinal aperture extending from said transverse aperture to the other end of the body, said bodies being mounted side by side with their transverse apertures in alignment, and a gas supply pipe extending through the transverse apertures and coupled to the adjacent end of each of the longitudinal apertures for supplying gas thereto.

5. In a gas burner, the combination of an elongate body having a transverse oblong aperture and a longitudinal aperture extending from said transverse aperture to the other end of the body, and a gas supply pipe extending into said transverse aperture and having a nipple extending into the adjacent end of the longitudinal aperture, the length of the nipple plus the external diameter of the gas pipe being less than the major dimension of the oblong aperture.

6. In a gas burner, the combination of an elongate body having a transverse oblong aperture and a longitudinal aperture extending from said transverse aperture to the other end of the body, a tube projecting into the oblong aperture and substantially filling the latter between its sides, a gas supply pipe housed by said tube, and means coupling the gas pipe to the adjacent end of the longitudinal aperture.

7. In a gas burner, a plurality of elongate bodies arranged in spaced parallel relation to form passages through which air may flow, each of said bodies being longitudinally apertured, a hollow post in each of said apertures, a series of nozzles projecting in spaced relation from one longitudinal edge of each of said bodies, and means housed by the posts for supplying fuel to said nozzles.

CARROLL CONE.
